SKIP-STITCH MECHANISM FOR BLIND-STITCH SEWING MACHINES

Frank Parry, Trumbull, Conn., assignor to The Singer Manufacturing Company, Elizabeth, N. J., a corporation of New Jersey

Application June 7, 1952, Serial No. 292,263

9 Claims. (Cl. 112—178)

1

This invention relates generally to improvements in sewing machines and, more particularly, to that type known as blind-stitch sewing machines.

It has for its primary object to provide an improved skip-stitch mechanism adapting the sewing machine for stitching together a plurality of plies of material, the stitches being caused to skip one of said plies at predetermined intervals in order to simulate hand stitching or minimize the "ladder" effect or stitch-exposure on the outer surface of the material encountered when stitching very thin materials.

Another object of the present invention is to provide a sewing machine having a skip-stitch mechanism in which only the ridge-former is periodically raised and lowered while the work-table is held stationary, thus eliminating the necessity of subjecting the actuating mechanism of the ridge-former to the additional load or work of overcoming the spring pressure normally exerted to maintain the work-table in its elevated position.

Still another object of the present invention is to provide a simplified skip-stitch mechanism for a blind-stitch machine in which the component parts of the mechanism are arranged so that they can be made relatively small and light in weight and, whereby the motions required for the operation are small, resulting in small inertia forces with the consequent smooth high speed operation of the machine.

The foregoing and other objects and advantages in view, together with means whereby the same may be carried into effect, will best be understood from the following description of a preferred embodiment thereof illustrated in the accompanying drawings, in which:

Fig. 1 is a top plan view of a blind-stitch sewing machine equipped with the present invention, certain of the cover-plates being removed and parts of the machine being in section better to show the operating mechanisms of the machine.

Fig. 2 represents a vertical sectional view taken substantially along the line 2—2, Fig. 1.

Fig. 3 represents an enlarged horizontal longitudinal sectional view of the work-table taken substantially along the line 3—3, Fig. 2, showing in detail the telescopic shaft arrangement of the skip-stitch mechanism.

Fig. 4 represents an enlarged vertical longitudinal sectional view of the work-table taken substantially along the line 4—4, Fig. 1.

Fig. 5 is an end elevation of the tubular ridge-former carrying shaft and its actuating rock-

2

lever with the eccentrically bodied internal supporting shaft in section, the view being taken substantially along the line 5—5, Fig. 4.

Fig. 6 is an end elevation of the eccentrically bodied supporting shaft and its actuating rock-lever, this view being taken substantially along the line 6—6, Fig. 4.

Fig. 7 represents an enlarged vertical sectional view through the machine-standard and substantially along the line 7—7, Fig. 1, illustrating the manner of supporting and driving the skip-stitch eccentric.

Fig. 8 represents a vertical sectional view taken substantially along the line 8—8, Fig. 7.

Fig. 9 represents an enlarged transverse section taken through the work-table substantially along the line 9—9, Fig. 1, showing the relative location of the ridge-forming element with respect to the stitch-forming mechanism and the feed-dog.

Fig. 10 represents an enlarged vertical section taken at the stitching point, showing the needle about to enter the work to form the anchor stitch.

Fig. 11 is a view similar to Fig. 10, but with the ridge-former at its lowered operative position in which the work is presented for the formation of the skip stitch.

Referring to the drawings, the sewing machine includes a machine-frame comprising a base 20 having a hollow standard 21 rising from the rear right hand corner thereof. Extending laterally towards the left from the upper end of the standard is a horizontal arm 22, and extending forwardly from the left hand end thereof is an arm 23. Attached to the free end of the arm 23 is a stationary presser-plate or foot 24 against which the work is clamped by a pair of conventional vertically yieldable work-clamping members 25 (Fig. 9) pivotally supported as at 26, adjacent the free end of a tubular work-table 27 which is supported by the base 20. Coil-springs 28, acting between the work-table 27 and the work-clamping members supporting bell-cranks 29, yieldingly urge the members 25 into work-clamping relation with the presser-plate 24.

Journalized in the horizontal arm 22 is a main rotary shaft 30 which, through the usual connections disclosed for example in the U. S. patent of Dearborn, No. 705,325, July 22, 1902, oscillates a needle-shaft 31 which is suitably journaled in the forwardly extending arm 23. Carried on the forward end of the needle shaft 31 is a curved needle 32 which oscillates directly above the presser-plate 24 and in a path transverse to the longitudinal axis of the needle shaft 31, the

forward or work-penetrating stroke being from left to right as viewed in Fig. 4. Cooperating with the needle 32 in the formation of chain-stitches is a looper 33 actuated, in the manner shown in the U. S. patent of Dearborn, No. 639,669, December 19, 1899, from the main-shaft 29. The work is fed rearwardly past the needle 32 by means of a four-motion feed-dog 34 which operates through a hole in the presser-foot 24 and in opposition to the vertically yieldable work-clamping members 25, all in a manner substantially like that disclosed in the U. S. patent of Dearborn, No. 1,592,446, July 13, 1926.

The work to be stitched is supported on the work-table 27 which is formed at its free left hand end as a tube or horn beneath the stitching and feeding mechanisms and at its right hand end is enlarged into substantially rectangular form having a convex upper surface closed, by a cover-plate 35 (Figs. 2 and 4), and a pair of depending end-walls 36 and 37. The means by which the work-table 27 is supported and the mechanism for controlling the normal elevated or working position of the work-table forms the subject of another of my copending applications Serial No. 292,261, filed June 7, 1952, and, therefore, only sufficient description will be herein-after given of the support for the work-table as will be necessary for a clear understanding of the present invention. Suffice it to say that the depending end-walls 36 and 37 of the work-table 27 are preferably fitted with bushings 38 and 39 (Fig. 1) in which are journaled the reduced eccentrically located opposite ends 40 and 41 of a work-table supporting shaft 42 freely journaled in the spaced upstanding lugs 43 and 44 integral with a bracket 45 detachably secured by screws 46 to the bed 20. Spring means is employed for yieldingly urging the work-table into its normal elevated work-presenting position determined by a stop-screw 47 which is threaded into the depending front wall 48 of the work-table 27, the stop-screw 41 at its inner end bearing against a stop-plate 49 (Figs. 1 and 2) secured by a screw 50 to an ear 51 cast on the bracket 45. Treadle or knee-shift controlled means is provided for pivotally lowering the work-table 27 about the eccentrically located ends 40 and 41 of the work-table supporting shaft 42. This means preferably includes a rock-shaft 52 (Fig. 1) journaled in a bracket 53 attached to the base 20 and having secured to it a rock-lever 54 connected at its inner end by a wire-link 55 to the work-table 27. The rock-shaft 52 is extended toward the front of the machine and is bent to extend across the front of and downwardly beneath the machine to form a knee-shift arm (not shown) which is adapted to carry a suitable knee-pad. Pressure applied to the knee-pad causes the work-table 27 to tilt downwardly about its pivotal support, thus moving the tubular portion of the work-table away from the overlying presser-foot to release the work.

The spring means employed for yieldingly urging the work-table 27 into its elevated position comprises a coil-spring 56 anchored at one end to a stud 57 endwise adjustable in the machine-frame, and at its other end connected to one end of a link 58 whose other end is connected to one limb of a bell-crank lever 59 pivoted at 60 on the ear 51. The other limb of the bell-crank lever 59 is connected by a link 61 to the depending front wall 48 of the work-table 27. It will be understood that lowering of the work-table 27 will cause the link 61 (Fig. 75

2) to move toward the left and this movement of the link 61, through the bell-crank 59, will cause the link 58 also to move toward the left, thereby extending the coil-spring 56. When the treadle or knee-shift is relieved of its pressure, the coil-spring 56 functions to return the work-table 27 to its elevated position.

As is customary, work-table height adjusting means is provided for adjusting the normal elevated position of the work-table 27, thereby to regulate the depth of penetration of the curved needle in the formation of the blind-stitch. The means illustrated in the drawings for accomplishing the adjusting of the table height is identical with that disclosed in my copending application hereinbefore referred to and, as shown in Figs. 1 and 2, includes a manually controlled member, the actuation of which turns the work-table supporting shaft 42 which, owing to the eccentrically disposed ends 40 and 41 thereof, results in bodily elevating or lowering the work-table 27 relative to the stitching mechanism. In Fig. 2 it will be seen that the work-table height adjusting means comprises a rock-lever 62 clamped on the work-table supporting shaft 42 and having connected thereto one end of a rearwardly extending link 63 which is connected at its other end to the lower end of a vertically disposed adjusting lever 64 fulcrumed intermediate its ends on a pivot-stud 65 fixed in a lug 66 preferably cast integral with one wall of the machine-standard 21. At its upper end, the adjusting lever 64 is formed as a yoke 67 of which the parallel limbs are slotted, as at 68, to receive the side pins 69 of a block 70 which is threaded upon an adjusting screw 71. The adjusting screw 71 is supported to turn but is confined against endwise movement in a detachable cover-plate 72 provided for closing the open front face of the machine-standard 21, and the adjusting screw has fixed thereto the manually controlled member which is in the form of a thumb disk 73. Indicia scribed in the peripheral face of the thumb-disk 73 facilitate the accurate adjustment of the normal elevated position of the work-table.

The work-table 27 provides supporting means for the usual ridge-former 74 (Figs. 3, 4 and 9) which function in cooperation with the presser-foot 24 in forming a bight in the material facilitating the penetration of the material by the curved needle 32 so as to form blind stitches. In the machine illustrated, the ridge-former 74 is oscillated in the line of feed with the forward stroke of the ridge-former coinciding with the forward or advancing stroke of the feed, and also the ridge-former is bodily raised and lowered so that shallow or skip stitches can be formed between successive deep or anchor stitches. The present invention is directed particularly to the mechanisms for actuating the ridge-former, whereby it is oscillated and simultaneously therewith bodily raised and lowered to effect presentation of the work to form skip stitches. Referring to Figs. 2, 3 and 4, it will be seen that the ridge-former 74 is preferably clamped upon the left hand end-portion of a tubular ridge-former carrying shaft 75 provided at its opposite ends with bearing bushings 76 by which the tubular shaft 75 is freely journaled on the enlarged ends 77 of an eccentrically disposed body of a telescopically arranged skip-stitch shaft 78 journaled at one end in a bearing-lug 79 and at its other end in a bearing-bracket 80 detachably secured by a screw 81 and a pin 82 to the work-table 27. At its right hand end, the tubular

shaft 75 has clamped on it a depending rock-lever 83 connected by a rearwardly extending link 84 to the depending arm 85 of a bell-crank lever freely fulcrumed on a skip-stitch pivot-spindle 86 which, as shown in Fig. 7, is preferably supported for freely turning movement in bearing bushings 87 fixed in the opposite walls of the machine-standard 21. The pivot-spindle 86 is confined in the bearing bushings 87 by two screws 88 threaded into the bushings. The rearwardly extending horizontal arm 89 of the bell-crank lever is connected to the lower end of a pitman 90 whose upper end embraces an eccentric 91 fast on the main-shaft 30. Rotation of the main-shaft 30 will effect a complete oscillation of the ridge-former 74 during each stitch-forming cycle and in a manner such that the forward stroke of the ridge-former coincides with the work-advancing stroke of the feeding mechanism so that the friction resulting from the forming of the bight in the work will not seriously hinder or interfere with the feed of the work. The height of the ridge-forming element 74 is normally set in accordance with the thickness of the material being sewn by manually adjusting the thumb-disk 73 which regulates the level of the work-table 21. When the ridge-former 74 is in the extreme forward end of its oscillating stroke, the work is properly positioned for penetration by the needle 32 (Figs. 10 and 11).

In order to form skip stitches between the anchor stitches, means is provided for turning, to a limited extent, the eccentrically bodied skip-stitch shaft 78. It will be understood that turning of the inner skip-stitch shaft 78 relative to the outer tubular shaft 75 effects a bodily drop of the outer tubular shaft and its ridge-former 74 relative to the needle 32 so that the latter in penetrating the work passes through less than the total plies of material folded over the ridge-former 74. For example, Fig. 10 of the drawings discloses the ridge-former 74 in its upper or elevated position, wherein the plies of material are raised relative to the needle 32 to a point where the needle penetrates all the plies, while in Fig. 11, the ridge-former is illustrated in its lower position, wherein the needle penetrates all but the bottom ply of the material. The means for periodically turning or oscillating the skip-stitch shaft 78 is best shown in Figs. 2, 3 and 7, and comprises a rock-lever 92 clamped on the right hand or distal end of the skip-stitch shaft 78 and having its lower end connected by a rearwardly extending pitman 93 embracing the outer race of a needle-bearing 94 (Fig. 7) mounted on an eccentric 95 which is preferably formed integral with a belt sprocket 96 freely journaled on the skip-stitch pivot-spindle 86. A disk 97 is secured upon the end-face of the eccentric 95 and is sufficiently large in diameter to provide a flange for maintaining the needle-bearing 94 in proper position on the eccentric 95. The belt-sprocket 96 is driven by a clip belt 98 which is driven from a smaller belt-sprocket 99 mounted on the main-shaft 30; the ratio of the belt-sprockets 96 and 99 being such that the eccentric 95 rotates at half the speed of the main-shaft 30. When so operating, alternate skip and anchor stitches are produced. It will be understood that the ratios of the belt-sprockets 96 and 99 may also be of the order of 3-to-1 or 4-to-1, in which case between each anchor stitch there will be formed three skip stitches or four skip stitches.

As will be observed in Figs. 1 and 4, the inner

skip-stitch shaft 78 has its opposite ends journaled in the spaced bearing lugs 79 and 80 with its right hand or distal end projecting beyond the bearing lug 79. The right hand end of the outer tubular shaft 75 terminates adjacent the bearing lug 79 in a manner such that the rock-lever 84 can be clamped on the outer tubular shaft adjacent one side face of the bearing lug 79, while on the distal end of the inner shaft 78 the rock-lever 92 can be secured next to the opposite side face of the bearing lug 79. This arrangement contributes to a rigid construction and permits the actuating connections 84 and 93 for the outer and inner shafts 75 and 78 to be housed within the base 20 of the main-frame and to transmit motion with a minimum of bending moment to the shafts 75 and 78 relative to their supporting bearings.

Having thus set forth the nature of the invention, what I claim herein is:

1. In a blind-stitch sewing machine, the combination with a main frame including an overhanging arm, of a stationary presser-plate attached to the free end of said arm and provided with an opening, stitch-forming mechanism mounted on said arm and including a needle mounted for movement across said opening, a work-table mounted on said main frame and having a portion underlying the free end of said overhanging arm, a ridge-forming element located below said presser-plate for projecting a ridge of fabric upwardly through said opening into needle penetrating position, an oscillatory outer tubular shaft on which said ridge-forming element is mounted, an oscillatory inner shaft journaled in said work-table and having at least one eccentrically disposed portion on which said tubular shaft is journaled, and actuating connections for oscillating said tubular and inner shafts at different frequencies thereby to raise and lower the field of action of said ridge-forming element at intervals relative to said needle to form anchor stitches and skip stitches.

2. In a blind-stitch sewing machine, the combination with a main frame including an overhanging arm, of a main shaft journaled in said arm and extending longitudinally thereof, a stationary presser-plate attached to the free end of said arm and provided with an opening, stitch-forming mechanism mounted on said arm and including a needle mounted for movement across said opening, a work-table mounted on said main-frame and having a portion underlying the free end of said overhanging arm, a ridge-forming element located below said presser-plate for projecting a ridge of fabric upwardly through said opening into needle penetrating position, an outer tubular shaft on which said ridge-forming element is mounted, an oscillatory inner shaft journaled in said work-table and having at least one eccentrically disposed portion on which said outer tubular shaft is carried, and actuating connections driven from said main-shaft for oscillating said inner shaft at a frequency different from that of the needle.

3. In a blind-stitch sewing machine, the combination with a main frame including an overhanging arm, of a main shaft journaled in said arm and extending longitudinally thereof, a stationary presser-plate attached to the free end of said arm and provided with an opening, stitch-forming mechanism mounted on said arm and including a needle mounted for movement across said opening, a work-table mounted on said main-frame and having a portion underlying the

free end of said overhanging arm, spaced shaft supporting bearing lugs provided on said work-table, a ridge-forming element located below said presser-plate for projecting a ridge of fabric upwardly through said opening into needle penetrating position, an outer tubular shaft located between said spaced bearing lugs and having mounted thereon said ridge-forming element, an oscillatory inner shaft journaled in said spaced bearing lugs and having at least one eccentrically disposed portion on which said outer tubular shaft is carried, and actuating connections driven from said main-shaft for oscillating said inner shaft at a frequency less than that of said needle.

4. In a blind-stitch sewing machine, the combination with a main-frame including an overhanging arm, of a main shaft journaled in said arm and extending longitudinally thereof, a stationary presser-plate attached to the free end of said arm and provided with an opening, stitch-forming mechanism mounted on said arm and including a needle mounted for movement across said opening, a work-table mounted on said main-frame and having a portion underlying the free end of said overhanging arm, spaced shaft-supporting bearing lugs provided on the opposite ends of said work-table, a ridge-forming element located below said presser-plate for projecting a ridge of fabric upwardly through said opening into needle-penetrating position, an oscillatory outer tubular shaft located between said spaced bearing lugs and having mounted thereon said ridge-forming element, an oscillatory inner shaft journaled in said spaced bearing lugs and having a distal end portion extending beyond the first of said bearing lugs, said inner shaft having at least one eccentrically disposed portion on which said outer tubular shaft is carried, a rock-lever secured on said tubular shaft adjacent one side of said first bearing lug, a second rock-lever secured on the distal end of said inner shaft adjacent the other side of said first bearing lug, and actuating connections driven by said main-shaft and operatively associated with said rock levers for imparting oscillations of different frequencies to said outer and inner shafts.

5. In a blind-stitch sewing machine, the combination with a main frame having a base, a standard and an overhanging arm, of a main shaft journaled in said arm and extending longitudinally thereof, a stationary presser-plate attached to the free end of said arm and provided with an opening, stitch-forming mechanism mounted on said arm and including a needle mounted for movement across said opening, a work-table mounted on said base and having a portion underlying the free end of said overhanging arm, a ridge-forming element located below said presser-plate for projecting a ridge of fabric upwardly through said opening into needle penetrating position, an oscillatory outer tubular shaft on which said ridge-forming element is mounted, an oscillatory inner shaft journaled in said work-table and having an eccentrically disposed portion on which said outer tubular shaft is carried, a pivot-spindle mounted in said standard below the level of said main-shaft, operating connections for said outer tubular shaft including an element journaled on said pivot-spindle and driven from said main-shaft, and operating connections for said inner shaft including a rotary actuator journaled on

said pivot-spindle and driven from said main-shaft.

6. In a blind-stitch sewing machine, the combination with a main frame having a base, a standard and an overhanging arm, of a main shaft journaled in said arm and extending longitudinally thereof, a stationary presser-plate attached to the free end of said arm and provided with an opening, stitch-forming mechanism mounted on said arm and including a needle mounted for movement across said opening, a work-table mounted on said base and having a portion underlying the free end of said overhanging arm, a ridge-forming element located below said presser-plate for projecting a ridge of fabric upwardly through said opening into needle penetrating position, an oscillatory outer tubular shaft on which said ridge-forming element is mounted, an oscillatory inner shaft journaled in said work-table and having an eccentrically disposed portion on which said outer tubular shaft is carried, a pivot-spindle mounted in said standard below the level of said main-shaft, actuating connections operated by said main-shaft for imparting oscillations to said outer tubular shaft, actuating connections for said inner shaft including a rotary actuator journaled on said pivot-spindle, and a belt connecting said rotary actuator to said main-shaft.

7. In a blind-stitch sewing machine, the combination with a main frame having a base, a standard and an overhanging arm, of a main shaft journaled in said arm and extending longitudinally thereof, a stationary presser-plate attached to the free end of said arm and provided with an opening, stitch-forming mechanism mounted on said arm and including a needle mounted for movement across said opening, a work-table mounted on said base and having a portion underlying the free end of said overhanging arm, a ridge-forming element located below said presser-plate for projecting a ridge of fabric upwardly through said opening into needle penetrating position, an oscillatory outer tubular shaft on which said ridge-forming element is mounted, an oscillatory inner shaft journaled in said work-table and having an eccentrically disposed portion on which said outer tubular shaft is carried, a pivot-spindle mounted in said standard below the level of said main-shaft, operating connections for said outer tubular shaft including an eccentric mounted on said main-shaft, a bell-crank lever journaled on said pivot-spindle, a pitman connecting said bell-crank lever to said eccentric, a link connected to said bell-crank lever, and a rock-arm connected at one end to said link and at its other end to said outer tubular shaft, and operating connections for said inner shaft including a second eccentric journaled on said pivot-spindle, means connected to said main-shaft for driving said second eccentric at a speed less than that of said main-shaft, a pitman connected to said second eccentric, and a rock-lever connected at one end to said pitman and at its other end to said inner shaft.

8. In a blind-stitch sewing machine, the combination with a main frame having a base, a standard and an overhanging arm, of a main shaft journaled in said arm and extending longitudinally thereof, a stationary presser-plate attached to the free end of said arm and provided with an opening, stitch-forming mechanism mounted on said arm and including a needle

mounted for movement across said opening, a work-table mounted on said base and having a portion underlying the free end of said overhanging arm, a ridge-forming element located below said presser-plate for projecting a ridge of fabric upwardly through said opening into needle penetrating position, an oscillatory outer tubular shaft on which said ridge-forming element is mounted, an oscillatory inner shaft journaled in said work-table and having an eccentrically disposed portion on which said outer tubular shaft is carried, a pivot-spindle mounted in said standard below the level of said main-shaft, operating connections driven by said main-shaft for imparting oscillatory movements to said outer tubular shaft, and operating connections for imparting oscillatory movements to said inner shaft including an eccentric mounted on said pivot-spindle, actuating connections between said eccentric and said inner shaft, a first belt-sprocket associated with said eccentric, a second belt-sprocket of smaller diameter than said first belt-sprocket mounted on said main-shaft, and a belt connecting said two belt-sprockets together.

9. In a blind-stitch sewing machine, the combination with a main frame including a hollow base U-shaped in cross-section and having an open top, a hollow standard having its side walls formed as continuations of the side walls of said base and having its front side open to form with the open top of said base a continuous opening extending from the front of the base to the top of the standard, and an overhanging arm extending laterally from the standard, of a stationary presser-plate attached to the free end of said arm and provided with an opening, stitch-form-

ing mechanism supported on said arm and including a needle mounted for endwise movement across said opening, a main-shaft journaled in the overhanging arm and having one end projecting into the upper end of said standard, a work-table mounted on said base and having one end-portion enlarged to overhang the front end-portion of said base, a ridge-forming element located below said presser-plate for projecting a ridge of fabric upwardly through said opening into needle-penetrating position, an oscillatory outer tubular ridge-forming element carrying shaft located in said work-table, an inner skip-stitch shaft journaled in said work-table and having an eccentrically disposed portion on which said outer tubular ridge-forming element carrying shaft is journaled, said outer and inner shafts having one end located in that portion of the work-table which overhangs said hollow base, actuating connections driven from such main-shaft for each of said inner and outer shafts, said actuating connections extending from said inner and outer shafts downwardly into said hollow base then backwardly within said hollow base to said hollow standard and then upwardly through said hollow standard to said main-shaft, and a cover plate closing said open-topped base and open-sided standard to cover and conceal said actuating connections.
